UNITED STATES PATENT OFFICE

155,729

DESIGN FOR A BEVERAGE VENDING MACHINE

Regis E. Parks, Brooklyn, N. Y., assignor to Spa-
carb, Inc., New York, N. Y., a corporation of
Delaware

Application December 31, 1947, Serial No. 143,487

Term of patent 14 years

(Cl. D52—3)

To all whom it may concern:

Be it known that I, Regis E. Parks, a citizen of the United States of America and resident of Brooklyn, county of Kings and State of New York, have invented a new, original, and ornamental Design for a Beverage Vending Machine, of which the following is a specification, reference being had to the accompanying drawings, forming part thereof.

Fig. 1 is a perspective view of a beverage vending machine, embodying my new design, as viewed toward a front corner of the machine; and

Fig. 2 is a side elevation of the machine as viewed toward the right side of the machine as shown in Fig. 1.

The rear and top of the machine are substantially plain in appearance.

I claim:

The ornamental design for a beverage vending machine, as shown and described.

REGIS E. PARKS.
